Application June 29, 1934, Serial No. 733,114

23 Claims. (Cl. 221—67)

This invention relates to improvements in a combination check-controlled and tell-tale operated means for keeping a mechanical check on the activities of a person concerned with the operation of a given device, which will be more fully explained hereafter.

One of the objects of this invention relates to closures for containers, and more particularly to a meter cap for the inlet conduit of a gasoline storage tank such as used by automobile service stations.

The practice of "night dumping", often followed by dishonest service station owners and operators, is the filling of gasoline storage tanks with cheap gasoline of low quality, this being sold at a higher price and dispensed through a pump bearing the brand of a high quality product. In a like manner, the high quality gasoline contained in such storage tanks is often blended with a quantity of low quality fuel and sold at a high price.

It is an object of our invention to provide a cap for the fill pipe of a gasoline storage tank that will leave a tell-tale record for each opening of the cap, thus making the practice of "night dumping" impossible without detection.

The high government taxes on the sale of gasoline for motor cars has greatly encouraged tax evasion by gasoline refineries, a practice that has risen to tremendous proportions due to recent increases in gasoline tax rates.

Another object of our invention is to provide a cap for a gasoline storage tank fill pipe that will prevent unauthorized access to such fill pipes by recording the number of times said cap is opened. This will provide a check on the number of dumps made and greatly assist the government in reducing such tax evasion to a minimum.

Another object of our invention is to provide a cap which is effectively locked to a fill pipe to prevent bodily removal of said cap without mutilation of a part thereof.

Another object of our invention is to provide a cap through which a storage tank may be gauged with a sounding stick while remaining substantially closed to the dumping of gasoline in the tank.

Another object of our invention is to provide means whereby, whenever the fill pipe is uncovered, a record of the act is made, and that the cap must be completely opened before closing and completely closed.

Another object is to provide means whereby a token must be inserted into the device to ef-

fect an opening and the token inserted is retained in the device. Also means whereby a token is discharged but not the token inserted.

Another object is to provide means whereby direct access to the token receiving mechanism and the magazine is prevented to prevent manipulation of the token operated mechanism.

Another object is to provide means whereby a suitable recording device, counting device or comptometer, may be actuated. Such recording device may be any of the many devices on the market adapted for the purpose. The recording device shown in the accompanying drawings is fully described in the pending application of Lewis Sharp and Peter P. Novak, Serial No. 636,133, filed October 4th, 1932, and is shown only as illustrating a suitable recording device.

Still another object of our invention is to provide a cap which is small in size and extremely simple in construction and operation.

Further objects and advantages will be made manifest in the following description taken in connection with the accompanying drawings in which:

Fig. 1 is a side view of the assembled device comprising our invention and showing the device in position as mounted upon the fill pipe of a storage tank.

Fig. 2 is a plan view of the assembled device in opened position revealing the end of the fill pipe to which it is attached and in which a portion is cut away to reveal the dial of a recording device and its location.

Fig. 3 is a sectional view on the line 3—3 of Fig. 4, disclosing the assembled parts therein in section, and when in closed position.

Fig. 4 is a fragmentary plan view showing the interior of a portion of the device when in open position.

Fig. 5 is a fragmentary sectional view on the line 5—5 of Fig. 1 showing in detail the method of attaching the device to the fill pipe.

Fig. 6 is a fragmentary sectional view of the line 6—6 of Fig. 1 showing more in detail the construction of cap portion of the device in position upon the end of the fill pipe.

Fig. 7 is a repetition of a portion of Fig. 6 showing a change in relative position of the parts.

Fig. 8 is an under plan view of the cork plate shown in section in Fig. 6.

Fig. 9 is an under view showing more in detail an assembly of the parts shown in section in Fig. 3.

Fig. 10 is a view showing more in detail one of the parts shown in Fig. 3.

Fig. 11 is a sectional view on the line 11—11 of Fig. 10.

Fig. 12 is a view showing more in detail one of the parts shown in Fig. 3.

5 Fig. 13 is an edge view of the member shown in plan in Fig. 12.

Fig. 14 is a plan view of another one of the parts shown in Fig. 3.

Fig. 15 is an edge view of the member shown 10 in Fig. 14.

Fig. 16 is a more detailed view of a portion of the device considered separate from the assembled device.

Fig. 17 is a fragmentary sectional view on the 15 line 17—17 of Fig. 16.

Fig. 18 is a sectional view on the line 18—18 of Fig. 16.

Fig. 19 is an under plan view of the device shown in Fig. 16.

20 Fig. 20 is a view of a suitable recording device or comptometer as used in our invention and showing the enclosing frame and actuating member.

Fig. 21 is a plan view of a transparent cover 25 shown in section in Fig. 3.

Fig. 22 is an edge view of the same with a portion broken away and shown in section.

Fig. 23 is a fragmentary section on the line 3—3 of Fig. 4.

30 Fig. 24 is an enlarged view of the stud and pawl shown in Figs. 4 and 23 and.

Fig. 25 is a section on the line 25—25 of Fig. 24.

Referring to the drawings with more particularity, our invention is embodied in a device 35 shown in assembled form in Figs. 1 and 2 and the accompanying more detailed drawings.

The bracket 1 is adapted to enclose the end of a fill pipe 2 by a sleeve portion 3. A webbed bracket 4 extends from the side wall of the sleeve 40 portion 3 and is split to allow the sleeve portion 3 to yield in a circumferential direction for clamping of the sleeve upon the fill pipe 2. The two halves of the webbed bracket 4 are drawn together by the bolt 5. To further insure the 45 proper and desired position of the sleeve portion 3 upon the fill pipe 2, a spring bolt 6 is disposed in a socket 7, preferably bored into the webbed bracket 4, and is urged by the spring 8 into a socket 9 in the wall of the fill pipe 2, as shown 50 more clearly in Fig. 5.

On the extremity of the webbed bracket 4 is a boss 10 supporting a plate 11 with which it is preferably integral. From the bottom of the supporting plate 11 depends a tube 12 through 55 which tokens are discharged from the hole 13 in the plate 11 as will be further explained hereinafter. In the boss 10 is a stud 14 held in fixed position by a set screw 15.

A cap member 16 is disposed rotatably upon 60 the plate 11, having a flanged portion 17 extending to enclose the plate 11 and having a web portion 18 drilled in its center to fit over the stud 14. In the web portion 18 is a hole 19 of the same size as the hole 13 in the plate 11 which registers 65 with the hole 13 when the cap member 16 is in full closed position, as shown in Fig. 3. Integral with the cap member 16 is a cap 20 shown in Figs. 1 and 2 and a fragmentary portion in Fig. 4, also in Figs. 6 and 7. The cap member 16 together 70 with the integral cap 20 is rotatable upon the plate 11 and when in closed position the cap 20 registers concentrically with the sleeve 3 and the fill pipe 2. Also integral with the cap member 16 is an extended cup member 21 preferably disposed at an angle to the axis line of the cap 75

member and cap, and having a web bottom 22. In said bottom is a central drill hole 23 and an arcuate slot 24. The flange 25 which forms the rim of the cup 21 has therein a slot 26.

Within the cup 21 a token receiver 27 is centrally and rotatably disposed, said receiver having 5

a knurled cap 28 by which the receiver may be rotated manually, and a base portion 29 which fits freely within the cup 21 when in operable 10

position. In the base of the receiver is a centrally located and threaded drill hole 30 into which the 15

cap screw 31 is screwed to hold the receiver in 20

position. In the base of the receiver 27 is also a fixed stud 32 which, when the receiver 27 is 25

in position in the cup 21, passes through the 30

arcuate slot 24 and by the slot is limited in movement, thus limiting the rotary movement of the 35

receiver 27. The under side of the base 29 of the receiver 27 is chambered with a concentric circular chamber 33 in which a coiled spring 34 is 40

disposed in such a manner that one end of the spring is attached to the receiver 27 by being 45

inserted into a hole 35 therein and the other end of the spring 34 is inserted in a hole 36 in the web 50

bottom 22 of the cup 21. The spring 34 is adapted 55

to urge the receiver 27 rotatively in a clockwise 60

direction. In the base 29 of the receiver 27 is a 65

token chamber 37 similar in form to a coin 70

chamber, as is seen in Fig. 18, and so positioned 75

that when the receiver 27 is rotated counter- 80

clockwise until the stud 32 reaches the end of the 85

arcuate slot 24 in the bottom of the cup 21, the 90

chamber 37 registers with the slot 26 in the rim of 95

the cup 21, at which position a coin or token may 100

be inserted through the slot 26 into the cham- 105

ber 37. In so doing it is necessary to press back 110

a plunger 38 against the resistance of the 115

compression spring 39 which is disposed in a drilled 120

plunger chamber 40 in the plane of the token 125

chamber 37. The spring 39 and plunger 38 tend 130

to urge the token out of the token chamber 37 135

until the receiver 27 is rotated clockwise by the 140

urge of the spring 34. These parts provide what 145

may be termed a check catapulting means. As 150

the receiver 27 rotates, the token is carried round 155

inside the flange 25 of the cup 21, the flange 25 160

holding the token from leaving the token cham- 165

ber 37 until such time as the token chamber 37 170

arrives at a point diametrically opposite the slot 175

26 and registers with a slot 41 in the wall of the 180

cup member 21. At this point the token is pushed 185

out of the token chamber 37 through the slot 41. 190

It will be seen that this action of the receiver 27 195

makes it act as a check discharging means.

Concentric with the flanged portion 17 of the 200

cap member 16 is a circular flange 16' extending 205

upward and forming a cup shaped chamber 41' 210

having the web 18 as a bottom and the slot 41' 215

communicates between the cup 21 and the cup 220

shaped chamber 41'. Within the chamber thus 225

formed is a ratchet plate 42 shown in detail in 230

Figs. 12 and 13. Through this ratchet plate is a 235

hole 43 which will be referred to herein as a 240

token magazine because the plate 42 is thick 245

enough to hold a plurality of tokens such as are 250

used with this device.

The tokens herein referred to are preferably 255

similar in size and shape to a one cent coin of 260

the U. S. coinage, though any suitable token may 265

be used for the purpose.

The ratchet plate 42 is centrally drilled with 270

a hole 44 and a concentric recess 45 disposed in 275

its upper face. Also in the upper face of the 280

ratchet plate 42 is a T-shaped pocket 46 in which 285

is disposed a flat stop 47, having an extension 290

arm 47'. Beneath the stop 47 and disposed in the pocket 46 is a coiled compression spring 48, shown in broken lines in Fig. 12, which tends to urge the stop 47 upward at its peripheral end. 5 The inner end of the stop 47 is hinged on a pin 49 shown in broken lines in Fig. 12.

The edge of plate 42 is cut away at 50 and 50' and its curved edge between 50 and 50' is notched to form a ratchet 51. In the bottom of the recess 10 45 is a drill hole 52 adapted to receive a drive pin 53 shown in Fig. 11.

In operable position, the plate 42 rests in the bottom of the cup shaped chamber 41' of the cap member 16 as shown in Figs. 3 and 4, the 15 stud 14 passing through the central drill hole 44. Upon the plate 42 the token holder plate 54 is disposed. This plate 54 is centrally drilled with the hole 55, and has a token receiving notch 56 in its edge. In its opposite edge is a retaining 20 notch 57. The token holder plate 54 is preferably slightly thicker than a token.

The plate 58 shown in detail in Figs. 10 and 11 has a central boss 59 which, when the parts are assembled, passes through the hole 55 of 25 plate 54 and rests in the recess 45 of plate 42 as shown in Fig. 3. In this position the stud 53 engages in the drill hole 52 of plate 42 to insure that the plates 58 and 42 remain stationary and do not rotate with the cap 16. Plate 58 has a 30 large concentric recess 60 to receive a suitable indicating and counting device 64 as shown assembled in Fig. 20. Plate 58 is provided with an annular groove 61 in which is disposed a pawl 62 having a detent 63 which extends into the recess 60 to engage and actuate the counting device 64 when the parts are assembled in operable position. The hole 55 is threaded to receive the threaded stud 14 to hold the parts in assembly as shown in Fig. 3.

40 When the parts are in assembled position as in Fig. 3, a glass cover 66 held in a frame 67 is disposed in the cup shaped chamber 41' of the cap member 16 to keep out moisture and foreign matter and the cup shaped chamber 41' is closed 45 by a cover 68.

In the bottom of the cup shaped chamber 41' is a stud 69 upon which is rotatably mounted a pawl 70 adapted to engage the ratchet 51. This ratchet and pawl are so constructed that when 50 the cap member 16 is rotated in one direction the pawl 70 drags across the ratchet and prevents the direction of rotation of the cap member from being reversed until the pawl has passed the end of the ratchet 51 and reached the cutaway place at 50 or 50' where the pawl may swing free of the ratchet. When the cap member 16 is rotated in the opposite direction the pawl is dragged across the ratchet as before but in the opposite direction and again prevents the direction of rotation of the cap member from being reversed. Studs 71 and 72 act as stops to limit 60 the movement of the cap member 16, Figs. 4 and 23.

To provide a spring action for the pawl 70, the stud 69 is cut away at 73 and the pawl has a portion cut away at 74 to provide shoulders 75 and 75' against which the spring 76 bears and tends to urge the pawl to a balanced or neutral position, as shown in Fig. 25, whenever rotated 70 in either direction.

In the inner face of the flange 16' is a pocket 77 seen in Fig. 23, and in broken lines in Fig. 4. When the plate 58 is in assembled position, as in Fig. 3, and is rotated in the cup shaped chamber 75 41', the pawl 62 drops into the pocket 77 when-

ever it passes that point and is again pressed back into the relative position shown in Fig. 10 as it leaves the pocket 77, which provides that the detent 63 of the pawl 62 is pressed inward every time the pawl leaves the pocket 77, and by so doing actuates the counting device 64 and makes a record of the movement.

When in operable assembly, the position of the plate 42 is determined by being held in synchronous and aligned position relative to the 10 plate 58 by the stud 53 and the plate 58 being attached securely to the stud 14 and the stud 14 being held securely in the boss 10 by the set screw 15. Therefore, when the cap member 16 is rotated about the stud 14, the plate 42 and the plate 58 remain stationary and do not move relative to the plate 11 and the boss 10. The 15 holder plate 54 moves with the cap member 16 and is moved thereby by the fixed stud 69 engaging in the notch 57 in the holder plate 54 as indicated in Fig. 3.

When the device is properly assembled as is shown in Figs. 1, 2 and 3, a plurality of tokens M reside in the token magazine 43, a sufficient number to completely fill the magazine. If the device 25 is in closed position as in Fig. 1, and the cap portion 10 is upon and in alignment with the sleeve 3 and fill pipe 2, the plate 42 is at its extreme clockwise movement and the stop 47 is opposite the slot 41.

In operation the receiver 21 is turned manually in a counter-clockwise direction until the token chamber 37 therein registers with the slot 26. A token is inserted through the slot 26 into the token chamber 37 against the resistance of the 35 plunger 38 and spring 39. When the receiver 21 is released it will be rotated in a clockwise direction by the spring 34 until the token chamber 37 registers with the slot 41 when the plunger 38 and spring 39 will push the token through the slot 41 into the token receiving notch 56 in the plate 54. In entering the receiving notch 56 the token compresses the stop 47 in the plate 42 which projects, when the parts are in this relative position, into the token receiving notch 56 of plate 54. 45 Until the stop 47 is compressed by a token the parts cannot be rotated because the stop 47 engages the edge of the notch 56, but when compressed and held down by the token, the plate 54 is then free to move relative to the plate 42. 50 The cap member 16 is swung round in clockwise direction carrying with it the plate 54 and the token, the plates 42 and 58 remaining stationary, being secured through the stud 14 to the boss 10. The movement is continued until the stop 12 55 strikes the shoulder of the plate 42, as in position shown in Fig. 4. During this movement it is impossible to reverse the movement because of the action of the ratchet 51 and pawl 70.

When the cap member 16 has reached the extreme open position, as indicated in Fig. 4, one of the tokens in the magazine 43 will drop down into the hole 19 in the bottom of web 18 and the token in the receiving notch 56 will drop down into the magazine 43 to take the space vacated by the lower token which dropped down into the hole 19. This action of the cap member 16 makes it 60 serve as a check replenishing means.

The cap member 16 may be swung back in the reverse direction after the pawl 70 has left the 70 ratchet 51 as explained before, and in this movement the token which has dropped into the hole 19 in the web 18 will be carried round until it is over the tube 12 and the hole 18 in the plate 11 and will fall out through the tube.

Thus the cap member 16 cannot be swung round to open position to open the fill pipe 2 until a token is inserted, as described, to release the stop 47, and when once started to open must continue 5 to full open before reversed. Also when opened to full one of the tokens in the magazine 43 is discharged and the new one is retained. The discharged one is dropped from the device when the cap member 16 is swung back to cap the fill pipe. 10 This operation of the cap member 16 makes it serve as a check stacker.

The object of this arrangement is to provide that an operator must put in a token before he can open the fill pipe and in return he does not 15 get the token he put in but one from the magazine. Because the cap has been opened and closed a record of the act is made by the counting device 64. If an operator uses an unauthorized token he leaves a record that the device has been 20 opened and he leaves his token in the magazine. In due time his token will be discharged and discovered by a later operator.

To prevent unauthorized operators from opening the device by means of pennies or other 25 tokens, the operating company may keep a register of their tokens or otherwise arrange that their tokens do not fall into the hands of unauthorized operators. The tokens may be numbered or dated or otherwise marked and it will 30 be observed that a stack of tokens M is initially located in the magazine and as the device is operated, tokens are added to the stack as often as tokens are withdrawn therefrom, hence the operator has to replenish the stack each time he 35 opens and closes the device.

The placement of the token receiver 27 as a medium whereby the tokens are introduced into the token operated mechanism is to prevent direct manipulation of the device through the 40 opening 41. The base of the token receiver 27 is interposed between the opening 26 and the opening 41 at all times.

To insure a perfect closure of the end of the fill pipe 2, and to provide means whereby a gauge 45 may be inserted into the tank through the fill pipe, and to provide means whereby the cap 20 may be secured to prevent tampering or possible breakage, the cap 20 is provided with a lug 78 to which is hinged a split link 79 on the pin 80, 50 the link 79 having therethrough a hole 81 for insertion of a lock-bar. In the link 79 is hinged an eccentric cam 82, with a handle extension 82', and hinged on the pin 83. On the side of the sleeve 3 is a lug 84 with a hole 85 therethrough 55 for the insertion of a lock-bar. When the cap 20 is in position upon the end of the fill pipe 2 the link 79 is dropped down over the lug 84 and the bar of a lock inserted through the hole 81 of the link 79 and the hole 85 of the lug 84 to prevent 60 opening until the lock-bar is removed. In bringing the link 79 into position over the lug 84, the cam 82 must register under the lug. The handle 82' is swung outward until the cam 82 will enter under the lug 84, then the handle 82' is pressed 65 down to bring the eccentric cam 82 into pressure against the under side of the lug 84 making a secure closure of the cap 20 upon the end of the fill pipe 2 and preventing the cap 20 from being raised.

70 The cap 20 is cut away on one side at 86 to facilitate its swinging over the end of the fill pipe 2, leaving a flange portion 87 to align against the pipe 2 and align with the sleeve 3. Centrally disposed within the cap 20 is a movable plate 88 75 having an annular recess therein filled with cork

89, which when the plate 88 is pressed down upon the end of the fill pipe makes a secure seal. A shank 90 of the plate 88 extends upward through a centrally located hole in the cap 20 and has on its upper end a cross-bar handle 91 by which the shank 90 and plate 88 may be rotated. Under the cross-bar 91 and against the top of the cap 20 is a spring 92 which tends to urge the cross-bar and shank 90 and plate 88 upward. In the upper face of the plate 88 are a plurality of balls 93 and 93' resting in sockets which allow the balls to protrude a little above the surface of the plate 88. At corresponding positions in the under face of the cap 20 are pits 94 and 94' into which the balls 93 and 93' may recede when in position to allow the plate 88 to abut against the under face of the cap 20. If the plate 88 is rotated, the balls 93 and 93' are forced out of the pits 94 and 94' and the balls rest against the under face of the cap 20, as shown in Fig. 7. This provides a means whereby the plate 88 is moved up and forced down. When forced down the cork 89 is forced against the end of the fill pipe 2, making a secure closure. Fig. 6 shows the balls in position in the pits 94 and 94' and Fig. 7 shows the balls out of the pits 94 and 94'. 20 25

Through the shank 90 a hole 95 is drilled to provide an opening through which a measuring rod may be inserted to measure the contents of the tank. This hole is stoppered by a threaded plug 96 which may be removed to insert a measuring rod without removing the cap. 30

Operation

To uncover the fill pipe an operator must remove the lock from the link 79 and disengage the cam 82 and link 79 from the lug 84. He must then turn the token receiver 27 until the slot 37 registers with the slot 26, insert a token through the slot 26 and allow the token receiver to rotate until the token registers with the slot 41. The spring 89 and plunger 88 will force the token into the receiving notch 58 of the plate 84. By so doing the stop 47 is compressed to allow the parts to rotate. The cap 20 may then be swung round to full opening. At this position a token will drop from the magazine 43 into the hole 19 in the web 18, and the inserted token will drop into the magazine to take the vacated place. When the cap 20 is swung back to close, the token in the hole 19 is carried round to the tube 12 where it is dropped when the cap 20 is in registering position on the fill pipe and the token will drop out. 40 45 50

During the movement of the parts the cam 82 will drop into the pocket 77 and out again, thus moving the detent back and forward to actuate the counting device. 55

Although we have shown and described but one preferred form of our invention, it is to be understood that many modifications and changes might be made therein without departing from the spirit and scope of the appended claims. 60

Having thus described our invention, what we claim is:

1. A device of the character described, comprising: a closing cap for a fill pipe; a locking means constructed and arranged to prevent opening movement of said cap until released by a token; means whereby said locking means is released by a token inserted in said device; and means constructed and arranged to retain the releasing token and discharge another token previously placed in said device upon full closing of the cap. 70 75

2. In a device as described, a check magazine, rotary means adapted to receive a check and movable automatically to deposit the same into magazine, means controlled by said rotary means for exchanging said check for another check, and means for automatically ejecting the latter check from the magazine. 5
3. In a device as described a token magazine, rotary means for ejecting a token from said magazine, means preventing ejection of tokens from said magazine, means for actuating the rotary means, and a device carried by said actuating means operable upon receipt of a token to render the preventing means abortive. 10
4. In a device as described, in combination with a check-discharger, a check magazine from which checks are ejected, and check catapulting means for supplying said magazine with checks. 15
5. In check-controlled apparatus a body, a support there adjacent formed with a cavity, a rotor in said cavity having an actuating handle, said support having diametrically opposed slots, one of which receives a check to be deposited into said rotor so as to be positioned by the latter opposite the other slot of said support, and means for automatically ejecting the check out of the latter slot. 20
6. In combination with a container having an inlet, a normally locked closure for said inlet, means operable upon receipt of a check to unlock said closure, and mechanism exchanging said check for another check, said mechanism being operated as said closure moves to expel said second check so as to tell-tale the movement of said closure. 25
7. In combination with a container having an inlet, means movable to cover and uncover the same, said means being operable upon receipt of a check, an actuator for said means, and mechanism controlled by said actuator for expelling another check upon closing of said inlet so as to serve as a tell-tale for said actuator. 30
8. In a device as described, a magazine for a stack of checks, mechanism ejecting a check from said stack to reduce the height of the stack, and mechanism actuated by the first mechanism to add a check to said stack and to restore the height of the stack. 35
9. In combination with a fill-pipe, a closure therefor, means for moving said closure off from said fill-pipe, means for anchoring said means on said fill-pipe against vertical and rotative displacement therefrom, a packing between the closure and the fill-pipe, and manually operable means accessible externally of the closure for pressing said packing against the fill-pipe. 40
10. In combination with a fill-pipe, a support disposed laterally thereof, means carried by said support embracing said fill-pipe for immovably anchoring the support upon the latter, a closure for said fill-pipe, and means mounted upon said support for swinging said closure to uncover said fill-pipe. 45
11. In a device of the character described, a check magazine, means adapted to receive and movable to deposit a check thereinto, and means operated with said first means for discharging out of said magazine a check different from the deposited check. 50
12. In a device of the character described, a check magazine, means adapted to receive and movable to deposit a check thereinto, manually operated means for actuating the same, and means controlled by said manually operated means and acting concurrently with the first means for ejecting from said magazine a check different from the first named check. 55
13. In a dispensing machine, a magazine, mechanism operable upon insertion of a token to open the machine and to pass said token into the said magazine when the machine is being opened, said mechanism being adapted to pass another token away from said magazine during the closing movement of the machine and to expel said second token when the machine is fully closed. 60
14. In a dispensing machine, a cover, a magazine, manual means for operating said cover, said means becoming automatically locked when the cover is moved into closed position, mechanism manually operable upon insertion of a token into the machine to unlock said cover operating means, devices associated with said cover operating means for passing the token into said magazine during the opening movement of the cover, and elements associated with the cover operative means for carrying another token away from the magazine and for expelling it upon closing of the cover. 65
15. In a dispensing machine, a normally locked closure, manual means operable upon the insertion of a token to unlock said closure and to deposit the inserted token into the machine, and means movable by said operating means for expelling another token from the machine upon the deposit of the first token into the machine. 70
16. In a dispensing machine having a normally locked closure, a magazine, manual means operable upon the insertion of a token to unlock said closure and for passing said token into the said magazine, and means operable by said manual means for extracting another token from the magazine and expelling it from the machine. 75
17. The combination with a container, of a cover normally locked in closed position, cover opening mechanism, mechanism released for operation upon insertion of a token to open the cover and devices associated with said mechanism to expel another token upon closing the cover. 80
18. The combination with a container, a stud, a cover mechanism pivotally hung on said stud, a member locking said mechanism against rotation on said stud in closed position, means operable upon insertion of a token to move said member to release the said mechanism to open the container, and devices associated with said releasing means to expel another token upon closing of said cover mechanism. 85
19. The combination with a container, a stud, a cover mechanism pivotally hung on said stud, a member locking said mechanism against rotation on said stud in closed position, means operable upon insertion of a token to move said member to release the said mechanism to open the container, means compelling full opening and full closing of said cover, a magazine for receiving the inserted token upon the opening of the cover and simultaneously to release another token, and devices associated with said releasing means for expelling said released token upon closing of the cover. 90
20. The combination with a token magazine, manually rotatable means having a slot for insertion of a token, resilient means yieldingly resisting insertion of said token, and means retaining said token in position during manual rotation, said retaining means having an opening through which the token is catapulted by said resilient means upon completion of said manual rotation. 95

21. In combination with a pivotally hung closure for a container, full stroke mechanism for said closure, operating means for said closure normally locked in closed position and released for operation upon insertion of a token, a counter recording each operation of the closure, and means for expelling another token from said operating means upon closing said closure.

22. In combination with a pivotally hung container cover, normally locked operating means having a token entrance opening and discharge opening, actuating means operable upon insertion of a token to catapult said token into the said token entrance thereby to release said oper-

ating means to open the cover, and means associated with said operating means for carrying another token to said discharge opening during the closing movement of the cover.

23. The combination with a pivotally hung container cover, of a full stroke mechanism for said cover, operating means for said cover normally locked in closed position and released for operation upon insertion of a token, means for recording each operation of the cover, and means for expelling said token from said operating means upon closing of the cover. 5 10

RALPH J. WHITLOCK.
LEWIS SHARP.

CERTIFICATE OF CORRECTION

Patent No. 2,077,601

April 20, 1937.

RALPH G. WHITLOCK, ET AL.

It is hereby certified that error appears in the above numbered patent requiring correction as follows: In the drawings, Sheet 2, Figure 3 should appear as shown below instead of as shown in the patent:

and that the said Letters Patent should be read with this correction therein
that the same may conform to the record of the case in the Patent Office.

Signed and sealed this 12th day of October, 1937.

(Seal)

Henry Van Arsdale.
Acting Commissioner of Patents.

21. In combination with a pivotally hung closure for a container, full stroke mechanism for said closure, operating means for said closure normally locked in closed position and released for operation upon insertion of a token, a counter recording each operation of the closure, and means for expelling another token from said operating means upon closing said closure.

22. In combination with a pivotally hung container cover, normally locked operating means having a token entrance opening and discharge opening, actuating means operable upon insertion of a token to catapult said token into the said token entrance thereby to release said oper-

ating means to open the cover, and means associated with said operating means for carrying another token to said discharge opening during the closing movement of the cover.

23. The combination with a pivotally hung container cover, of a full stroke mechanism for said cover, operating means for said cover normally locked in closed position and released for operation upon insertion of a token, means for recording each operation of the cover, and means for expelling said token from said operating means upon closing of the cover. 5 10
